(57) **CLAIM**

The ornamental design for an arthropod trapping device, as shown and described.

DESCRIPTION

FIG. 1 is a front, right-side isometric view of an embodiment of an arthropod trapping device;

FIG. 2 is a rear, left-side isometric view of the arthropod trapping device of FIG. 1;

FIG. 3 is a front view of the arthropod trapping device of FIG. 1;

FIG. 4 is a right side view of the arthropod trapping device of FIG. 1;

FIG. 5 is a rear view of the arthropod trapping device of FIG. 1;

FIG. 6 is a left side view of the arthropod trapping device of FIG. 1;

FIG. 7 is a top view of the arthropod trapping device of FIG. 1; and,

FIG. 8 is a bottom view of the arthropod trapping device of FIG. 1.

The drawings include shadows and reflections that indicate contour, not surface ornamentation.
